US0D1040013S

(12) **United States Design Patent** (10) **Patent No.:** **US D1,040,013 S**
(45) **Date of Patent:** **** Aug. 27, 2024**

(54) **HYDROPONIC PLANTER**

(71) Applicant: **Just Vertical Incorporated**, Brampton (CA)

(72) Inventors: **Conner Thomas Shaw Tidd**, Toronto (CA); **Kevin Jakiela**, Kitchener (CA); **Thomas Wong**, Brampton (CA); **Randy Yang**, North York (CA); **Kamil Musielak**, Mississauga (CA); **Lisa Margaret Cooper**, North York (CA); **Akinsola Oluwafemi Salami**, Toronto (CA)

(73) Assignee: **Just Vertical Incorporated**, Brampton (CA)

(**) Term: **15 Years**

(21) Appl. No.: **29/820,259**

(22) Filed: **Dec. 21, 2021**

(51) LOC (14) Cl. **11-02**

(52) U.S. Cl.

USPC **D11/144**

(57) **CLAIM**

The ornamental design for a hydroponic planter, as shown and described.

DESCRIPTION

FIG. 1 is a front-top perspective view of a hydroponic planter showing my new design;

FIG. 2 is a rear-bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the drawings depict portions of the hydroponic planter that form no part of the claimed design.

1 Claim, 6 Drawing Sheets
